TRAFFIC SIGNALING SYSTEM

Vincent W. Leonard, Fort Wayne, Ind., assignor
to General Electric Company, a corporation of
New York

Application January 6, 1930, Serial No. 418,805

11 Claims. (Cl. 177—339)

My invention relates to traffic signaling systems and to apparatus especially adapted for use therein. More particularly the invention relates to the type of system in which the signals are adapted to be operated automatically from a central point; to a system in which a given relation is maintained between the signals at consecutive road intersections along a given highway; and to a system in which the signals are operated from a central point and in which the relation mentioned may be changed from the said central point without the necessity of having to send someone to each intersection.

In certain types of traffic signaling systems it is common practice at times to operate the light signals along a highway, such as the green signals, simultaneously. At other times the signals may be operated progressively at a particular rate and at still different times these same signals 20 may be operated progressively at a different rate. Heretofore such changes have been carried out by sending someone to each controller, or receiver as it is sometimes called, to set it in proper relation to the other controllers along the highway. It is an object of my invention to provide 25 a traffic signaling system with means whereby such changes may be made from a central point. It is an object to provide means such that if the signals are operating in such manner that the 30 green signals along the highway all come on simultaneously they may be reset from a central point to appear progressively and such that, when desired, the control apparatus may be reset again back to the original relation so that all the green 35 signals may again appear simultaneously. In other words, it is an object of the invention to provide, what I have called, a double reset signal.

The following detailed description will enable 40 the features of the invention to be more fully understood, reference being had to the accompanying drawings in which Fig. 1 shows a system, in diagrammatic form, comprising the features of the invention. In this figure the apparatus indicated in the upper part of the drawing represents two of a series of intersections and a signal station at each along a main highway with the corresponding set of signals of each station under the control of a local receiver. In the 45 lower part of the drawing the apparatus there indicated represents the central station apparatus, including the transmitter, through the medium of which the receivers are operated. Portions of the double reset means are located at the 50 various intersections in the receivers and por-

tions are located at the central station, forming part also of the central apparatus.

Fig. 2 shows the transmitter of the central apparatus without the reset means of Fig. 1 in perspective. 5

Fig. 3 shows diagrammatically the transmitter of Fig. 2 and the portion of the reset means that belongs in the central office diagrammatically.

Fig. 4 shows in perspective one of the receivers of Fig. 1 for controlling the signals at one of the 10 intersections.

Fig. 5 shows the same device in a so-called exploded view and in perspective.

Fig. 6 shows the receiver of Figs. 4 and 5 diagrammatically. 15

Fig. 7 shows in plan view a modification of one of the sets of contact springs used in the receiver of Fig. 4.

Fig. 8 shows a section taken along line 8—8, Fig. 7, viewed in the direction indicated by the 20 arrows.

Fig. 9 is a section taken along line 9—9, Fig. 7, in the direction indicated by the arrows.

Fig. 10 is a modification in perspective of the ratchet driving arm, Fig. 6, and of the pin thereon. 25

Fig. 11 shows a section taken along the axis of one of the pins on the arm, Fig. 10.

Figs. 12, 13, and 14 are diagrammatic representations of different relations of the receivers along a highway. Fig. 12 shows the receivers in 30 synchronism and arranged to maintain the signals in a relation of non-progression. Fig. 13 shows the same receivers out of synchronism. Fig. 14 shows the same receivers in synchronism, indicating the double reset means and indicating a 35 relation of progression of the signals.

Fig. 15 shows the same receivers in synchronism and in such relation as to produce non-progression of the signals.

Fig. 16 is a plan view of a modification of one 40 of the elements of the receiver, Fig. 6.

Referring more in detail to the drawings, the transmitter shown in Figs. 2 and 3 and in the lower part of Fig. 1 is operated by any suitable motor. In the drawings an induction motor M 45 is indicated for this purpose comprising an armature disk 2 and a pair of field magnets 3 adapted to be connected to any source of current such as the ordinary light or power circuit. The armature 2 is connected, through a series of 50 gears, see Fig. 3, with a shaft 4, on which latter are mounted a pair of cams 5 and 6 for operating the impulse springs 7 and 8 respectively with respect to their corresponding contacts 9 and 10, through the medium of which springs the im- 55

pulses are produced for operating the receivers along the highway. For this purpose the springs 7 and 8 are connected respectively with conductors 7' and 8' and the contacts 9 and 10 with the conductor 9'.

On the same shaft 4, to the right of cams 5 and 6, Fig. 3, there is mounted another gear 11 in mesh with the gear 12 for operating a cam 13 included in the timing or reset means of the systems through the medium of which cam the contact springs 14, 15, and 16 are operated, said springs constituting also part of the reset mechanism. The said springs, as shown, are connected respectively with the conductors 17, 18, and 19.

The motor is provided as usual with a pair of shading coils 20 and 21 for regulating the speed of the motor. These shading coils are mounted on the ends of the cores of the coils 3, next to the disk 2, one on each side thereof. The shading coil 20 is mounted on an adjustable shaft 22 for varying the position of this shading coil about the axis of the shaft with respect to the shading coil 21. This adjustment is facilitated by the provision of a lever 23 on the end of the shaft 22, through the medium of which lever the shaft may be rotated any suitable degree about its axis, thus correspondingly varying the position of the shading coil 20.

In the group of gears shown in Fig. 3 for driving the shaft 4, gear shifting means is provided for varying the speed of rotation of the shaft 4, this shifting means comprising a pair of gears 24 and 25 which are secured together on the sleeve 26, which latter is in driving engagement with the shaft 4, but may be slid along the shaft either to the right or to the left for the purpose of bringing the gear 24 into engagement with the gear 27, for producing one rate of rotation of the shaft or for substituting the gear 25 in engagement with the gear 28 for producing a different rate of rotation. It will be understood that when the gear 24 is in engagement with the gear 27 the gear 25 is out of engagement with the gear 28, and vice versa. The shifting operation of these gears 24 and 25 is accomplished through the medium of the lever 29, which latter is connected with a cam element 30, see Fig. 2. This cam element, as shown, is provided with a slot 31, through which a pin 32 extends. This pin is located on the shaft 33 to rotate therewith for shifting the cam 30 to the right or to the left as the case may be depending upon whether the pin 32 is rotated either clockwise or counter-clockwise, Fig. 2. To facilitate this movement of the cam 30, a lever 34 is provided on the end of the shaft 33. By operating the lever 34, the gears 24 and 25 may be shifted back and forth on the shaft 4 for the purpose described.

In Fig. 1 a pair of receivers A and B is shown connected in multiple and for this purpose a cable comprising conductors 35, 36, 37, 38, and 39 is provided. While I have shown only two receivers any number may be connected in multiple along the same cable. Each of these receivers 65 consists mainly of a circuit controller, a motor for driving the controller, contacts operated by the controller in a predetermined sequence to correspondingly energize the intersection signals, and a part of the synchronizing or double reset, mechanism. As shown the conductors 38 and 39 of the cable are connected with a suitable source of current G, such as a direct current generator, one terminal of which generator is connected to the conductor 39 and the other terminal of which is grounded, the conductor 38

being also shown grounded to complete the circuit.

It will be understood that the receivers are duplicates of each other and therefore it will be sufficient to describe the receiver A in detail. In Fig. 1 the corresponding parts of the receivers A and B are shown similarly located. The receiver A includes a ratchet step-by-step mechanism which is operated through the medium of a pair of electromagnets 40 and 41, which I have represented as solenoids. These electromagnets are energized alternately to oscillate the arm 42 about the axis of a shaft 43, see Fig. 5. Arm 42 is a part of the ratchet mechanism and is provided with a pair of pins 44 and 45 for engaging alternately the teeth shown on the periphery of the detent wheel 46. The wheel 46 is adapted to rotate, along with a disk 47, about the axis of a shaft 47', the rotation being produced by the alternate energization of the magnets 40 and 41, which effect alternate engagement of the pins 44 and 45 with the teeth on the wheel 46. Disk 47 is provided near its periphery with a ring of perforations 48, see Fig. 4. For use in connection with these perforations I provide a pair of pins 49 and 50, either one of which is adapted to be placed in engagement with any one of the perforations. Preferably these pins may be threaded and the perforations may be correspondingly threaded so that the pins may be screwed into place. In proximity of the disk 47 I provide a set of contact springs 51 and 52, each of which is provided with a set of contacts, the spring 51 with the contacts 53 and 54 and the spring 52 with the contacts 55 and 56, the contacts 53 and 55 being on one side and the contacts 54 and 56 on the opposite side of their corresponding springs. As indicated in Fig. 1 and as shown in Fig. 6, the spring 52 is provided with a stem 57 and the spring 51 with a stem 58, both of which stems, as shown in Fig. 4, are mounted in operative relation with respect to the disk 47, the relation being such that the stem 57 stands in the path of the pin 50, whereas the stem 58 stands in the path of the pin 49. As shown in Fig. 4, in the preferred arrangement the stems 57 and 58 are folded over toward the disk 47, the stem 58 being folded over the stem 57 and standing sufficiently above the head of the pin 50 so that the pin 50 may pass under the stem 58 without operating the latter, but operating the stem 57. On the other hand, the pin 49 is made with a diameter sufficiently small to enable it to pass by the stem 57 without operating the latter and sufficiently high to engage the forward portion of the stem 58 for operating the latter. The springs 51 and 52 and the pins 49 and 50, as will be more fully explained, constitute part of the double reset mechanism. The double reset means also comprises an electromagnet relay at each receiver. For example, the reset mechanism at the receiver A comprises the relay 59, which latter has under its control the contact spring 60 and a pair of corresponding contacts 61 and 62, between which contacts the spring 60 is located. Through the medium of the electromagnet 59 the spring 60 may be made to engage either one or the other of the said contacts. When the spring 60 is in engagement with the contact 62, that is, when the electromagnet is deenergized, the solenoid 40 is under the control of the spring 52 and therefore under the control of the pin 50. When the electromagnet 59 is energized and the spring 60 is in engagement with the contact 61, the electro-

magnet 40 is under the control of the spring 51 and therefore under the control of the pin 49.

Referring to Fig. 4, it will be seen that the stems 57 and 58 project through the front plate 63 of the frame of the receiver, which plate, as shown, is hinged to the box 64, which encloses the whole mechanism of the receiver. Referring to Figs. 4 and 5, it will be seen that the solenoids 40 and 41 are secured to the back plate 65 of the receiver. The two plates 63 and 65 of the frame are adapted to be secured through the medium of the posts 66 and screws 67, which latter extend through suitable perforations in the plate 65 and engage the threads in the ends of the posts 66.

As shown in Fig. 5, the electromagnet 59 is also secured to the plate 65 and in any suitable manner.

Beyond the detent wheel 46 and adapted to rotate therewith and located along the shaft 47, see Figs. 5 and 6, a number of cams are provided which are divided into two sets. One set comprises the cams 68, 69, and 70, and the other set comprising the cams 71 and 72. Through the medium of the first set of cams the arm 73 is operated for operating in turn the contact springs 74, 75, 76, and 77 with respect to their corresponding contacts 78, 79, 80, and 81 respectively. As shown in Fig. 6, the springs 74 and 75 are connected with conductors 82 and 83 respectively, while springs 76 and 77 are connected with conductors 84 and 85 respectively. Also the contacts 78 and 79 are mounted on the conducting support 86 which latter is connected with conductor 86, while contacts 80 and 81 are mounted on the conducting support 82 which latter is connected with conductor 87.

The other set of cams, that is, the cams 71 and 72, is used for controlling an arm 88, the function of which arm is to restore the arm 73 to its initial position. For example, as the shaft 47' advances under the action of the magnets 40 and 41, the arm 73 passes from the larger diameter of cam 68 to the cam 69 of the same diameter, thence down on cam 70, and finally back in engagement with the cam 68 on the lower diameter thereof. While the arm 73 is in this last position the arm 88 passes from the higher diameter of cam 71 to the cam 72 of the same diameter, and thence to the intermediate diameter of cam 71 and finally to the lower diameter of cam 71, reaching this lower diameter in two steps. The result of this arrangement is that as the shaft 47' rotates, the arm 73 oscillates, oscillating in turn the stem 89 of insulating material mounted on the outer end of the arm 73 for operating the springs 74 through 77. During each cycle of operation the stem 89 assumes four different positions, as indicated by the four parallel lines a—a, b—b, c—c, d—d, Figs. 1 and 7, with the result that the signals R, AM, and G, indicating respectively red, amber and green, along the main highway and R, AC, and G, indicating respectively red, amber and green, along the cross road are operated in proper sequence. For example, in the position c—c the arm 73 is in the highest position, that is, in the position of largest diameter of the cam 68. In this position the contacts 75 and 79 will be in engagement, giving the G signal on the main highway and the R signal on the cross road. The arm next passes to the position d—d, in which position the above signals persist, and in addition, the contacts 77 and 81 are in engagement and the signals AM come on, indicating caution on the main highway. In the next position a—a the signals above indicated are all retired and in-

stead thereof the signal R appears on the main highway and G on the cross road, the contact 74 engaging the contact 78. It is at this point that arm 88 and the cams 71 and 72 come into play, carrying the arm 73 back to an intermediate position indicated by the line b—b, in which position the contact 76 engages the contact 80 and the amber signal AC comes on, indicating caution on the cross road. From this point the arm 73 is then carried to the original position c—c, after which the signal is repeated. This specific signal control means forms the subject matter of and is more fully described in the U. S. Patent 1,851,247, issued March 29, 1932 to Chester I. Hall.

For the purpose of adjustment, the shaft 47', to which the cam 70, Fig. 4, is secured, terminates in a lever arm 70'; the cam 69 is secured to a sleeve 120, over the shaft 47' that terminates in the lever arm 69'; the cam 72 is secured to a sleeve 121 that terminates in a lever arm 72'; the sleeve 120 passing through the sleeve 121; also the detent wheel 46 and the cam 71 are secured in common to a sleeve 122 that terminates in the disk 47, the sleeve 121 extending through the sleeve 122. The cam 68 rides loosely on the sleeve 120 but is locked to the cam 71 through the medium of the stem 123, as shown. With this arrangement the cams 69, 70, 72 may be adjusted with respect to each other and to the remaining cams about the axis of the shaft 47', which is common to all of the cams, to the wheel 46, and to the disk 47. Through the medium of the said lever arms all of the cams and the wheel 46, the disk 47 and the lever arms themselves all normally rotate in unison when the wheel 46 is rotating inasmuch as all of these elements are interlocked through the medium of the interlocking medium shown in front of the frame plate 63, which interlocking mechanism comprises the lever arms mentioned, suitable detents thereon and the serrated marginal portions shown in Fig. 4.

Referring to Figs. 4 and 5, it will be seen that the springs 74 through 77 and their corresponding contacts 78 through 81 are supported by a block 90 of insulating material, the springs 74 through 77 being secured thereto on the forward side as shown in Fig. 4, and the contact supports 91 and 92 being secured to the rear side as shown in Fig. 5. The block 90 is in turn secured to the frame of the receiver in any suitable manner as for example between the plates 63 and 65 through the medium of screws for example, the block being shown provided with openings 93, on both sides for this purpose.

Referring to Figs. 7, 8, and 9, the detail of a preferred form of construction and the method of assembly of the springs under the control of the arm 73 and of the corresponding contacts are shown. In these figures the springs are numbered 74' through 77' and the corresponding contacts 91 and 92. It will be seen that all of these elements are supported on an element 90' of insulating material. As shown in Figs. 8 and 9, the contacts 91 and 92 are secured to the rear of the element 90', while the springs 74' through 77' are mounted on the opposite side, see Fig. 7, these springs being pivotally held in place by means of a pin 93, the head of which, as shown in Fig. 9, is threaded, being shown in this figure in threaded engagement with the element 90'. This pin is locked in position by means of a nut 94. Each of the springs 74' through 77' is mounted on a separate base of insulating material. For example, the spring 75', Fig. 8 is mounted on the element 95 through which the pin 93 passes. This

element 95 is formed with a heel extending toward the rear of the unit, Fig. 8, under which heel a coiled spring 96 is provided for normally biasing the element 95, and therefore the spring 15' toward its corresponding contact 79 on the element 91. Each of the springs is provided with a similar supporting and biasing structure. Electrical connection is maintained between the springs 75', for example, and the corresponding terminal 97 by means of the flexible conductor 98. A similar means of connection is provided between the spring 74' and the terminal 99, the spring 76' and the terminal 100 and between the spring 77' and its terminal 101.

Figs. 10 and 11 show a modification of arm 42, Fig. 5, and of the pins thereon. It will be seen that the pins 44' and 45' on the arm 42' for operating the detent wheel 46 are not rigidly mounted on the supporting arm, but are flexibly mounted in order to soften the stroke between each pin and the detents on the wheel 46. The nature of this flexible arrangement is clearly illustrated in Fig. 11, the pin 45' being inserted in a conical opening in the element 42' in order to enable it to shift in any direction about the central axis of the opening against the cushioning action of a coiled spring 102 the pin being normally biased in the position shown in Fig. 11 by the coiled spring.

Referring again to Fig. 6, the details of the operating means between the springs 51 and 52 and the dial 47 including the pins 49 and 50 and the stems 57 and 58 are clearly shown. As shown, both of these elements 57 and 58 are mounted on a common shaft 103, about the axis of which either of the elements 57 and 58 is adapted to be oscillated independently of the other by the corresponding pins 50 and 49. The springs 51 and 52 are normally biased so that the contacts 54 and 56 are normally engaged by the respective springs, and elements 57 and 58 are biased towards the disk 47. The illustration is so clear that it is thought that no further description than that already given is necessary for a full and clear understanding of the relation between the disk 47, the pins 49 and 50, the elements 57 and 58, and the springs 51 and 52.

In this same Figure 6, the relation between the relay 59 and its spring 60 is clearly shown, the relay 59 being provided with an armature 104, through the medium of which the spring 60 is operated back and forth between the contacts 61 and 62.

Referring again to Fig. 1, and in particular to the cam 13 near the bottom of the drawing with its springs 14, 15, and 16, in the position shown the springs 15 and 16 are in engagement while the spring 14 is maintained out of engagement with the spring 15 by means of a pin 105, which latter is secured to the spring 16. As the cam advances in its rotation in the direction indicated by the arrow the spring 16 clears the heel 106 of the cam and falls on to the surface 107. As a result the spring 16 disengages from the spring 15 and a substitute connection is established between springs 15 and 14. As the cam continues to advance the spring 15 also clears the heel 106, at which time the original relation of the springs, that is, the relation shown in the drawings is reestablished until the cam makes another revolution, whereupon the same operation is repeated. Therefore, the springs 14 and 15 remain in contact for only a short interval during each cycle or revolution of the cam. In the system of Fig. 1 when the receivers A, B, etc. are in

synchronism, all of the respective springs 52 operate in synchronism with the spring 15 under the control of the cam 13. The same is true with respect to the respective springs 51 of the receivers, that is, the springs 51 operate in synchronism with the spring 15 under the control of the cam. The relation of all of the receivers is such that when they are in synchronism the springs 51 or 52 are in engagement with their corresponding contacts 54 or 56 at each receiver 10 at the same time that the spring 15 is in engagement with the spring 16 and also springs 51 or 52 are in engagement with their corresponding contacts 53 or 55 at each receiver at the time that the spring 15 is in engagement with the 15 spring 14. If, from any cause any receiver falls out of synchronism with the transmitter, the disc 47 of such receiver will be brought to a stop until the transmitter catches up, as will be more fully described. The function of the cam 13 and 20 of the reset elements comprising springs 51 and 52 and the pins 49 and 50 is to automatically maintain the receivers in synchronism. But before describing this feature I will describe how the synchronizing operation may be obtained 25 manually after which the automatic resynchronizing operation will be more easily understood. For example, the motor M being in operation, the springs 7 and 8 are operated to alternately send impulses along the cable conductors 36 and 37 by way of their corresponding contacts 9 and 10. Assuming that all of the receiver springs 52 are in engagement with their corresponding contacts 56, as indicated at station B, Fig. 1, and that the relays 59 are all deenergized, as indicated at stations A and B, and that receiver A is ahead of receiver B, as indicated, the impulses will operate the solenoids 40 and 41 alternately, advancing the disks 47 of all of the receivers in unison, in the direction indicated by the arrows, 40 even though the receivers are not in synchronism. The path of the impulses through the solenoids 41 is as follows: From the source of current G, over the cable conductor 38 and over the branch conductor 108 and conductor 9' to the contact 9, 45 thence by way of spring 7, conductors 7', 36 and 118, to and through the solenoid 41, thence by way of conductor 111 to the cable conductor 38, to ground and back to the source of current. The path of the impulses through the solenoids 50 40 is as follows: From the source of current G, over the same path as far as the conductor 9', thence by way of contact 10 and spring 8, conductor 8' and switch 112 to the cable conductor 37, thence by way of branch conductor 113 through 55 the contact 56 and spring 52 and by way of contact 62 and spring 60 through the solenoid 40, and thence by way of conductors 111 and 38 and back to ground. In the due course of rotation of the disks 47 of station A, the pin 50 advances 60 into engagement with the stem 57, as indicated at station A, the final movement being effected by magnet 41. The result is that the spring 52 is shifted from contact 56 to contact 55 and that the circuit for the solenoid 40 is interrupted, it 65 being understood that switch 114 at the transmitter is open. The receiver B, however, since it is indicated as being behind and out of synchronism with receiver A will continue to advance until its pin 50 reaches stem 57, and when 70 its pin 50 reaches its stem 57 the receiver B will also stop for the same reason as receiver A, at which time the spring 52 is shifted from contact 56 into engagement with contact 55. At any time thereafter if switch 114 is closed all of the re- 75

ceivers will again advance simultaneously in synchronism inasmuch as the reset or alternate circuit is closed for the solenoids 40 by way of switch 114. As a result, the disks 47 are advanced 5 one step, whereupon the springs 52 all fall back into engagement with their corresponding contacts 56. From this point on the solenoid 40 continues to be energized alternately with the sole- 10 noid 41 over the original circuit by way of the switch 112.

As long as the switches 112 and 114 are both closed, the disks 47 will continue to advance indefinitely even though one of the receivers were to fall behind the other. However, if a traffic 15 officer, for example, were to report that one or more of the receivers are out of synchronism, as indicated in Fig. 13, the central office attendant will open the switch 114 for an interval of time longer than the time that it takes a disk 47 to 20 make a complete rotation, 100 seconds, for example. The result is that all the receivers will be again brought into synchronism, as indicated in Fig. 12, and upon closing the switch 114 again the resynchronized receivers will then proceed to 25 operate in synchronism. It will be seen, therefore, that by the manual operation of the switch 114 any receiver that has fallen out of step with the remaining receivers may be brought back into 30 synchronism from the central office by the attendant.

Having described how the equipment may be operated manually to resynchronize the receivers, I will now proceed to explain how the synchronization may be automatically maintained 35 through the medium of the cam 13 which may be considered as a substitute for the switches 114 and 112, and as a means for automatically periodically closing and opening the same circuits.

In order to substitute the automatic resyn- 40 chronizing means for the manual the switches 112 and 114 are left open and the switch 115 is closed. As a result of this change, the path over which the solenoid 40 is energized is changed so as to reach the cable conductors 37 and 35 by 45 way of the spring 15 and of the springs 14 and 16, but the path over which the solenoid 41 is energized is not affected.

Again assuming that the springs 52 are in engagement with the contacts 56 as shown in connection with station B the impulses from the spring 8 pass over the conductor 8', thence by way of switch 115 to the springs 15 and 16 (when the springs 15 and 16 are in contact), thence by way of the conductor 19 to the cable conductor 37 and by way of the contacts 56 and springs 52, contact 62, springs 60, to the solenoid 40 and back to the source of current. Assuming that these impulses bring the disks 47 of stations A, B, C, Fig. 12, into the positions of synchronism indicated and that at the same time the spring 16 clears the heel 106, the alternate or reset circuit for the solenoids 40 is closed when the spring 14 engages the spring 15. The next impulse from contact spring 8 will therefore find a closed path 60 over the reset circuit by way of the springs 15 and 14, contacts 55 and springs 52, with the result that the receiver A, as well as the receivers B and C, Fig. 12, will advance and restore each its springs 52 into engagement with the correspond- 65 ing contact 56. By that time the spring 15 under the control of the cam 13 also clears the heel 106 of the cam, thereby restoring the original energizing circuit for the solenoids 40 by way of the springs 16 and 15, contacts 56 and their corre- 70 75

sponding springs 52 over which circuit the receivers are carried forward in synchronism.

With the foregoing arrangement, therefore, if any receiver such as the receiver A, Fig. 1, or receivers A, B, or C, Fig. 13, reaches the position, 5 indicated in Fig. 12, in which the pins 50 engage the stems 51, before the cam 13 places the springs 14 and 15 in contact, these receivers will stop and wait in this position until the spring 16 clears the heel 106 of the cam 13. At that instant all of 10 the receivers that have fallen out of step with cam 13 will start forward in synchronism.

Let us now assume that all of the pins 50 of the receivers A, B, and C are placed in one of the holes 48 of the disks 47 which may be designated 15 as the zero position corresponding for example with the radius r , as indicated in Fig. 12. That being the case, if the receivers are all operated in synchronism the cams of the various receivers will be maintained in a relation which we will 20 assume to be such that the green signals will all operate simultaneously along the main highway. Under such conditions the cams behind disks 47, and therefore the cams that control the arms 13 may be said to have no angular displacement. 25 This relation I have diagrammatically illustrated in Fig. 12, where I have indicated with receivers A and B a third receiver C along the main highway of Fig. 1. In Fig. 13 I have indicated the condition that would exist when the receivers are 30 out of synchronism, the displacement being indicated by the displacement of the radii r which I have assumed to be 45° between A and B and 45° between B and C. All of these receivers in Fig. 13 may be brought back into synchronism, as in- 35 dicated in Fig. 12, by the method already indicated, either manually or automatically. That is, they may be brought back manually by opening the switches 114 and 115 and closing the switch 112 a sufficient length of time to bring all the re- 40 ceivers to a stop with no angular displacement between the radii r of the various receivers as in Fig. 12. Thereupon closing the switch 114 will cause the receivers all to start simultaneously in synchronism, it being assumed that the green sig- 45 nals under such conditions come on simultane- ously.

The same result may be obtained automatically by opening the switches 112 and 114 and closing the switch 115 and leaving it so, as already de- 50 scribed.

If it is desired to have the signals operate pro- 55 gressively, as for example so that each green signal comes on a given interval after the green signal of the preceding station, this can be done by displacing the pins 50, as indicated in Fig. 14, along the radii r , s , and t . I have indicated a phase displacement of 45°. Assuming the time of revolution of the disk 47 to be 100 seconds, the lapse of time between two succeeding green sig- 60 nals, will, of course, be 12½ seconds.

In order to enable the signals to be brought back into a condition, or phrase relation of non- progression, that is, so that the green signals for example, will all come on simultaneously, the pins 65 48 of the receivers A, B, and C may each be placed in a hole 48 along the radius y , Fig. 15, which is assumed to be the 275° radius with respect to radius r . In other words, there is no phase dis- 70 placement between the radii of the stations A, B, and C when the receivers are in synchronism. For a better understanding of the invention I have also shown in this figure the radii r , s , and t and the pins 50. It will be seen from Fig. 15 that the displacement between the radii r and y 75

is the same at each station, while the displacement with respect to s and t , which produces a progression, varies.

With the arrangement of the pins 49 and 50, as indicated in Figs. 14 and 15, the change from progression to non-progression of the group of green signals along the main highway, for example, consisting of one signal in each set, may be obtained from the central point by closing the switch 116, while switches 112 and 114 are open and 115 is closed. The result of this closure is that all of the reset relays 59 will be energized in multiple by a flow of current from the source G. As soon as these relays are energized at the stations A, B, etc., the contact springs 60 will be shifted from engagement with their contacts 61, thus substituting the second reset springs 51 and their corresponding contacts 54 and 53 for the springs 52 and their corresponding contacts 55 and 56 for the control of solenoids 40. As long as the springs 51 remain in engagement with the corresponding contacts 54 the solenoids 40 will be energized as before over the cable conductor 37 as a result of impulses transmitted through the medium of the contact 10 and contact spring 8 at the transmitter, the energizing circuit extending by way of cable conductor 37, contacts 54, springs 51, contacts 61, and spring 60, to the solenoids 40. The energization of solenoids 40, however, is over the same paths as before and the alternate energization of the solenoids 40 and 41 will cause the receivers to advance simultaneously. It will be seen that while any relay 59 is energized the pin 50 of the corresponding receiver has no effect on the corresponding solenoids 40. Instead of the pin 50 the pin 49 now plays the same part played by the pin 50 except that the operation is now directed to the spring 51. When the disk 47 advances so that the pin 49 engages the stem 58 the original energizing circuit for the magnet 40 is interrupted and an alternate or reset circuit is substituted therefor by way of contact spring 51, contact 53, cable conductor 35 and springs 14 and 15. The operation of each solenoid 40 over the alternate or reset circuit advances the disk 47 so that the corresponding pin 49 disengages the stem 58, thus allowing the springs 51 to fall back and restore the original circuits of the solenoids 40. Obviously, therefore, as long as the relays 59 are energized the receivers A, B, and C may be maintained in synchronism through the medium of the pins 49. Therefore, if the pins 49 are set along the radius y , as indicated in Fig. 15, then as stated, the disks 47 will all line up in synchronism, as indicated in this figure, with the result that the traffic signals will be operated in a non-progressive manner, for example, so that the green signals will appear simultaneously.

Obviously, when the pins 49 line up as shown in Fig. 15, the pins 50 will become displaced as shown, as long as the relays 59 are energized this displacement will be of no significance, but if it is desired to restore the signals from non-progression, Fig. 15, to progression, Fig. 14, this can be done by opening the switch 116, thereby deenergizing the relays 59 and switching the reset control to the pins 50, which will automatically realine these pins 50 as indicated in Fig. 14, restoring the order of progression. In each of these Figures 12, 13, 14, and 15, it is assumed that the green signal comes on when the radius r passes a given position, represented by the line L—L. However, some other radius may be selected and also some other position. This can

be done by changing the angular relations of the cams 68 through 72, the arms 73 and 88 and the disks 47 with respect to each other. Referring to Fig. 14, therefore, inasmuch as the radii r of the stations, A, B and C are displaced with respect to line L—L, the green signals will appear in progression, that is, in a displaced order. In Fig. 15 there is no such displacement between the radii r of the different stations, indicating therefore that there is no progression. The same thing is true with respect to Fig. 12. On the other hand, referring to Fig. 13, since the disks 47 are not in synchronism, the green signals will come on in a displaced order, but each disk 47A and 47B will come to a stop when it reaches line L—L until the cam 13 catches up.

With the means described, therefore, it is possible from a central point, or in other words from a central control point, to automatically shift from progression to non-progression by means of the switch 116. In other words, when the switch 116 is open the pins 50 determine one rate of progression. When the switch 116 is closed the pins 49 determine another rate of progression or non-progression. In either case, of course, the synchronism of the disks may be obtained either manually or automatically, depending upon whether the switch 115 is closed and the switches 114 and 112 open or not, as previously described.

For the sake of clearness I have described in the foregoing the location of the pins 49 along the radii y but the pins 49 may be located on any other set of radii having the same angular value, as for example, along the radii r . However, when radii r are used, inasmuch as in disk 47 of receiver A the hole 48 at the end of the radius r must be used for both progression and non-progression, a special double pin such as that shown in Fig. 16 must be used, which double pin combines the features of pins 50 and 49, the upper portion of the pin representing the pin 49 and the lower portion thereof representing the pin 50.

It will be understood that while I have described the invention in connection with the specific apparatus illustrated, I do not care to be limited to such specific apparatus, inasmuch as I contemplate modifications and variations within the spirit of the invention and the scope of the claims contained herein.

What I claim as new and desire to secure by Letters Patent of the United States is:

1. In combination, a plurality of circuit controllers, signals operated by each circuit controller in predetermined sequence, means for continuously operating said circuit controllers, means for synchronizing said circuit controllers including a plurality of synchronizing circuits connected to the said controller operating means, each synchronizing circuit being adapted to maintain the circuit controllers in a different timed relation relatively to each other, and means for rendering any one of said synchronizing circuits operative.

2. In combination, a plurality of circuit controllers, contacts operated by said circuit controllers in predetermined sequence, means for operating said circuit controller simultaneously in any one of a plurality of different relations relative to each other, and means operable from a central point for stopping all said circuit controllers in any one of said plurality of different relations and for starting them in operation in such relation.

3. In combination, a plurality of circuit controllers, means for operating said controllers, signals operated in predetermined sequence by said circuit controllers, a member which rotates with each circuit controller, each member having a plurality of adjustable projections, means controlled by said projections for effecting stopping of its controller, and means operable from a central point for rendering one or another of said projections at each circuit controller operative.
4. In combination, a plurality of circuit controllers, means for operating said controllers, signals operated in predetermined sequence by said circuit controllers, a member which rotates with each circuit controller, each member having a plurality of adjustable projections, means controlled by said projections for effecting stopping of its controller, means operable from a central point for rendering one or another of said projections at each circuit controller operative, and means for maintaining said circuit controllers in the adjusted relation relatively to each other for which they are set.
5. In combination, a plurality of circuit controllers, each provided with contacts operated in a predetermined sequence, signals connected to said contacts, means for operating said circuit controllers in timed relation relatively to each other, a plurality of synchronizing circuits, means actuated by said controllers and operable through said circuits for synchronizing said circuit controllers, said means serving to maintain said circuit controllers in a different timed relation relatively to each other through each of said synchronizing circuits, and means located at a central point for selecting the synchronizing circuit through which said controllers will be maintained in a predetermined timed relation relatively to each other.
6. In a traffic-signaling system, the combination of corresponding traffic signals located at street intersections, circuit controllers for operating the signals at each intersection respectively, means for driving said controllers, means for synchronizing said controllers in any one of a plurality of operating relations including a synchronizing circuit, a plurality of means operated by each controller for cooperating with said synchronizing circuit for maintaining a predetermined position of said controller relative to the other controllers in the system, each of said means maintaining said controller in a different relative position to the other controllers in the system, and means located at a central point for simultaneously selecting the position of each controller with respect to the other controllers in the system.
7. In combination, a plurality of circuit controllers spaced from each other, means for operating said circuit controllers in a predetermined phase relation relatively to each other, means for maintaining said circuit controllers in synchronism in the established phase relation, and means for simultaneously changing the operating position of each of said circuit controllers for changing the said phase relation of said circuit controllers to another predetermined phase relation.
8. In combination, a plurality of circuit controllers located at street intersections respectively, a plurality of traffic signals operated by each circuit controller in a predetermined sequence, means for continuously operating said circuit controllers in a predetermined phase relation relatively to each other, and means operable from a central point for simultaneously changing the operating positions of said circuit controllers for operating corresponding traffic signals in a different predetermined phase relation relatively to each other.
9. In combination, a plurality of separately driven circuit controllers spaced from each other, a plurality of signals operated by each circuit controller in predetermined sequence, means for driving said controller, common timing means cooperating with said driving means for continuously operating said circuit controllers in a predetermined phase relation relatively to each other, means operable from a central point for simultaneously changing the operating position of each of the circuit controllers for operating said signals in a different predetermined timed relation relatively to each other, and means for maintaining the circuit controllers in synchronism in its selected phase relation.
10. In combination, a plurality of circuit controllers spaced from each other, means for driving said controllers, means for operating said controller in any one of a plurality of predetermined phase relations including means operable by each circuit controller for determining its operating position in each of said phase relations, and means controlled from a central control point for cooperating with said controller operated means to enable said circuit controllers to simultaneously select their respective predetermined operating positions in each of said phase relations, and means for maintaining said circuit controllers in the selected relative positions.
11. In combination, a plurality of traffic signal controllers located respectively at traffic control stations, traffic signals operated through a predetermined cycle by said controllers respectively, means for driving said controllers respectively, means for operating said controllers in any one of a plurality of predetermined phase relations including means operated by each controller for determining its operating position and signaling cycle in each of said phase relations, means cooperating with said controller operated means for simultaneously selecting a predetermined one of said operating positions of each controller, and means for maintaining the controllers in synchronism in the selected operating positions.

VINCENT W. LEONARD.
